[57] CLAIM

The ornamental design for a height measurement device, as shown and described.

DESCRIPTION

FIG. 1 is a perspective view showing the front, top and left sides of the height measurement device, embodying the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a perspective view showing the front, top and left sides of the design in an alternative position of adjustment.

FIG. 1

FIG. 2

FIG. 3

FIG. 4

FIG. 5

FIG. 6

FIG. 7

FIG. 8
